ROLLER SCREEN

Frank Zega, Bridgeport, Conn.

Application November 23, 1945, Serial No. 630,258

6 Claims. (Cl. 160—23)

1

This invention relates to improvements in roller screens and panes for use with windows of dwellings and other building structures.

An object of the invention is to provide an improved roller pane or screen attachment which may be detachably mounted in an out-of-the-way place on the window frame, preferably on the exterior thereof, the pane or screening element of the attachment being conveniently extendable to cover and screen the opening, and retractable within a housing when not in use, and the housing and contained element being instantly detachable from the window frame without tools, for storage and to permit use of framed storm windows if so desired. My roller attachment thus may be quickly mounted on and removed from the window frame, as is done with the conventional type of framed screens or panes, yet it occupies but very little space in storage as compared with the latter, and is much smaller and lighter in weight, and therefore more easily installed and removed.

In accomplishing this object I provide, by the present invention, a housing and pane or screening element adapted to be detachably mounted on and supported by novel brackets, which latter I permanently secure to the window frame to remain as a part of such, the brackets being so arranged as to not interfere with the installing of framed storm windows when the roller screen attachment has been removed from the window frame. For guiding and confirming the opposite vertical edge portions of the pane or screening element when the latter is extended I provide novel vertical guides which are permanently secured to each of the two uprights of the frame and arranged so as to be substantially unnoticeable and to not interfere with operation of the window sashes, or with installation of storm windows.

A feature of my invention is the provision of a novel handle means secured to the exterior or leading edge of the pane or screening element, said means being so arranged as to not interfere with the operation of the window sashes at any time, and especially when the element is rolled up and not in use, and said handle means also serving to enable the element to be quickly and conveniently operated and to be easily and securely fastened in extended position across the window opening.

Another feature of my invention is the provision of novel means for preventing the leading edge and handle means of the pane or screening element from being inadvertently entirely with-

2

drawn into the housing at the time it is retracted and rolled around the spring roller, and therefore the handle means are always accessible, ready to be grasped.

5 Another feature of the present invention is the provision of reinforcing bars which extend transversely across the pane or screening element, and which serve to support the element in a flat or planar position, and to prevent the opposite side edges of the element from being inadvertently pulled out of the vertical guides provided for them when the element is in extended position.

10 Still another feature of the invention is the provision of means extending along the side edges of the pane or screening element for preventing excessive wear, and sticking or binding of the element where it rides in the vertical guides, and for supporting the transverse reinforcing bars in predetermined uniformly spaced positions, in accurate parallelism, the said means also serving to prevent the side edges of the element from pulling out of the vertical guides provided for them.

15 Other features and advantages will hereinafter appear.

20 25 In the accompanying drawings:

Figure 1 is a view showing the outside of a window frame in elevation, with the roller screen attachment of the present invention installed thereon, the screening element being extended across the opening of the window.

25 Fig. 2 is a vertical section taken on the line 2—2 of Fig. 1.

Fig. 3 is a fragmentary horizontal section taken on the line 3—3 of Fig. 1.

30 35 Fig. 4 is a fragmentary view taken along line 4—4 of Fig. 1 showing in elevation one end of the housing of the attachment, mounted on its associated bracket, which latter is secured adjacent the top or head of the window frame.

40 Fig. 5 is a view similar to Fig. 4, taken along line 5—5 of Fig. 1 showing the other end of the housing and the other supporting bracket.

45 Fig. 6 is a fragmentary vertical section through the housing and screening element of the attachment, the element being in retracted or rolled-up position on the roller.

Fig. 7 is a view, partly in elevation and partly in vertical section, of the housing, screening element and roller carrying the latter, one of the handles secured to the screening element being also shown.

50 Fig. 8 is a view looking in the direction of the arrows 8, 8 of Fig. 7.

Fig. 9 is a view similar to Fig. 8 except that the

end plate of the housing has been removed to reveal the interior arrangement.

Fig. 10 is a view of the inside of the end plate which was removed from the housing of Fig. 9.

Fig. 11 is a view of a roller-pane element, partially unrolled from the spring roller of the attachment, one handle of the element also being shown, and

Fig. 12 is a fragmentary horizontal section taken through the screen guide or channel secured to the side wall of the frame, and through one edge portion of the screening element, a reinforcing rod carried by the element being also shown.

Referring to Figs. 1 and 2, the roller screen attachment of the present invention is shown mounted on a window frame 10 having jambs or uprights 11, a head 12, and a sill 13. The side walls 14 of the uprights 11 have the usual sash-guiding strips 15 and molding 16 for confining and guiding the upper and lower sashes 17 and 18 respectively of the window.

According to the present invention I provide a novel roller screen attachment, including a spring roller 19 and housing 20 adapted to be demountably secured in an out-of-the-way place to the window frame 10, preferably on the exterior of the frame at the top thereof, under the head trim 12a. This attachment is so arranged as to enable its installation and removal to be quickly and conveniently accomplished without the use of tools, and its size and weight are exceedingly small, so that it can be more readily stored than the conventional frame screen, and more easily manipulated during the installation and removal. The brackets and guides for the attachment, which are left permanently on the window frame, are inconspicuous and do not interfere in any way with the operation of the sashes, or with installation of storm windows.

In the embodiment of the invention illustrated herein, the housing 20 of the attachment preferably comprises two sheet metal members 21 and 22, which may advantageously be made of sheet aluminum, Fig. 9, the latter member being roughly angular in cross-section, having a flat side 22a and a slightly curved or convex side 22b bulging outward to provide space around the spring roller 19. The top, longitudinally extending edge of the side 22b has an out-turned flange 22c which is secured to one edge portion of the member 21 by rivets 23, the said edge portion having a depending flange 24 overhanging the joint between the two members, and acting as a watershed, as illustrated in Figs. 2 and 9. The upper edge portion of the flat side 22a of the member 22 is turned outwardly and downwardly at approximately a 45° angle, to form a longitudinally extending depending flange 25 the edge 26 of which is folded under and back on itself so as to provide a smooth edge surface, as shown in Figs. 8 and 9.

The sheet metal member 21 of the housing has flat sides 21a and 21b extended at a slight angle with respect to each other, the edge portion of the latter side having a depending longitudinal flange 27, the lower part 28 of which is turned outwardly at approximately a right angle.

The housing 20 is provided with end plates 29 and 30, Figs. 7, 8 and 10, the latter plate having inturned flanges 30a extending inside of and frictionally engaging the associated right hand ends of the members 21 and 22 as viewed in Fig. 7, and said ends are provided with notches 31, Fig. 9, to receive lugs 32 on the end plate for the purpose of enabling the latter to fit flush with the ends

of the members, and to prevent the plate from being pushed further into the housing. The other end plate 29, in the left end of the housing, referring to Fig. 7, has inturned apertured lugs 33 by means of which it is secured to the members 21 and 22 through the use of rivets 34 as shown.

By this construction the housing 20 has an elongate opening 35, Fig. 9, extending for its entire length, adapted to enable a screening element 36 carried on the roller 19 to pass therethrough and be extended downward across the opening of the window frame.

For the purpose of rotatably mounting the roller 19 in the housing 20, the roller has bearing pins 37 and 38 projecting from its ends, extending through apertures in the end plates 29 and 30 respectively, the pin 38 being preferably flat and keyed to the end plate 30 so that the spring 39 within the roller (Fig. 1) may be wound up and the roller operated to maintain a tension on the screening element 36 in the manner of a roller shade.

According to my invention, I provide novel bracket means for demountably securing the housing 20 in place on the window frame 10 whereby the housing may be quickly installed on or removed from the frame without the use of tools. This means comprises, in the preferred embodiment of the invention illustrated herein, metal brackets 40 and 41 in the form of thin flat plates, preferably of aluminum, which are secured to the side walls 14 of the uprights 11 by screws 42, Figs. 4 and 5. The screw apertures in the brackets 40 and 41 are preferably countersunk, and the screws 42 are preferably flat head screws which, when driven deeply in, will fit flush with the surface of the brackets. Thus since the brackets are formed of thin material, they will occupy very little space on the side walls 14 of the frame and will not interfere with the installation of storm windows, since the clearances between the storm windows and the frame will not be materially lessened. However, if the said clearances are small to begin with, the brackets 40 and 41 may be recessed in the side walls 14 of the frame, so as to fit flush with the walls.

As shown in Fig. 5, the bracket 41 has an outwardly extended lug 41a which is apertured to receive the bearing pin 37 of the screen roller 19. In Fig. 4, the bracket 40 is provided with an open-ended slot 40a which extends upwardly at an angle toward the center of the bracket and is adapted to receive the flat bearing pin 38 of the roller 19 and to lock the pin against turning. The housing 20 and roller 19 carried thereby may thus be quickly and conveniently mounted on the brackets 40 and 41 by manipulating it to first insert the bearing pin 37 in the bracket 41 and then slide the flat bearing pin 38 laterally into the groove 40a.

In order to lock the bearing pin 38 in the groove 40a, and to enable the pin to be freed at will for removal of the housing 20 from the frame 10, I provide a locking pin or bar 43 axially movable in bearings 44 which are secured to the housing bracket 40, the bar 43 when in extended position as shown in Fig. 4 normally blocking the bearing pin 38 against lateral movement out of the slot 40a. As shown, the bar 43 may carry an extension spring 45 by which it is yieldably held in the extended position shown, and may have a knob 46 to be grasped for moving the bar 43 downward to clear the slot and free the bearing pin 38.

In accordance with the present invention, I provide novel guiding means for the side edge portions of the screening element 36, said guiding means being so arranged as to be conveniently permanently mounted on the outer set of sash guides 15 and yet not interfere with movement of the upper sash 17, nor with installation of storm windows on the frame 10. Referring to Fig. 3, my novel guiding means comprises a pair of angles 47 and 48 secured to a base strip 49, all of said parts being secured to the sash guide 15 by wood screws 50 screwed into the said guide. The angles 47 and 48, and the strip 49 may be advantageously made of aluminum, and it will be noted that the angles and the base strip do not project beyond the opposite sides of the sash guide 15, but are flush therewith. Thus the operation of the window sash 17 is not interfered with, nor is there any obstruction to the installation of storm window. For this reason, my guiding means comprising the angles 47 and 48 and the base strip 49 may be left permanently attached to the window frame even when the housing 20 and roller 19 carried thereby are removed for storage.

According to this invention the screening element 36, which may be of metal mesh, but is preferably formed of plastic, is provided with flat ribbons 51 along both sides of its opposite edge portions, the ribbons being of spring material such as phosphor bronze, and being secured at their leading ends to the ends of a channel-shaped clamping strip 52 which clamps the leading edge of the screening element 36.

For purposes of reinforcement, the screening element 36 is provided with reinforcing rods 54, as shown in Figs. 1 and 12, said rods being preferably of brass or bronze, and extending transversely across the element between the opposite side edges thereof, and being secured to the strips 51 by any suitable means such as brazing or soldering. The rods 54 are also secured to the screening element 36 at intervals, by tying these together with wire or string, as shown at 55, Fig. 12.

By this construction the reinforcing rods 54 maintain the flexible strips 51 properly spaced apart, and by being secured to the screening element 36, tend to maintain the latter in a flat plane when the element is extended downward across the opening of the window frame. The ribbons 51 extending along the opposite sides of the edge portions of the screening element are secured together at intervals to hold the screening element between them and to prevent the element from being inadvertently pulled out of the channels comprising the angles 47 and 48.

For the purpose of conveniently lowering and raising the screening element 36, and to secure it in lowered position, I provide novel handles 56, Figs. 8 and 9, in the form of elongate plates having hinged portions 57 which are secured to the channel strip 52 at the leading edge of the screening element. As shown in Fig. 6, when the screening element 36 is rolled up in its retracted position, the handles 56 hang from the leading edge of the element so as to not interfere with the operation of the upper sash 17 of the window.

When it is desired to extend or lower the screening element across the window opening, the handles 56 are grasped and pulled downward to extend the element across the window opening. On the threshold 13 of the frame I provide a pair of wing screws 58 adapted to be received in slots 59 in the handles 56, so that the latter may be

locked to the window sill as shown in Figs. 2 and 3, to hold the screening element 36 in extended position.

Referring to Fig. 9, it will be noted that the down-turned flange 25 of the sheet metal member 22 of the housing acts as a smooth and rounded bearing surface over which the screening element 36 and strips 51 slide, thus preventing excessive wear on the strips and element.

To prevent the screening element from being inadvertently completely withdrawn into the housing 20, hooks 60 are provided, secured to the channel strip 52 at the leading edge of the screening element, said hooks being adapted to engage the depending flange 25 when the screening element 36 is wound on the roller 19.

As shown in Fig. 11, a flexible pane element 61, which may be of transparent plastic or other like material, may be substituted for the screening element 36, thereby converting my improved roller attachment for use as a storm window. The side edges of the pane element 61 are carried between the flexible ribbons 51 in the same manner as the screening element 36 is carried, and the leading edge of the element is similarly secured within the channel strip 52. Suitable plastic strap means (not shown) may be employed for securing the rods 54 to the pane element 61 at intervals, as will be evident to those skilled in the art.

In use, for each window of a dwelling a pair of my improved roller attachments may be provided, one having a screening element 36 and the other having a pane element 61, the latter attachment being installed during the winter months, at which time the attachment having the screening element may be conveniently stored away. Since the bearing pins 37 and 38, and the housings 20 of both of the above attachments are identical, either attachment may be used with the one set of brackets 40, 41 which are permanently installed on the window frame.

Although in the foregoing description for the sake of convenience I have considered the screening element 36 as comprising a mesh, and the element 61 as comprising a flexible imperforate pane, it should be understood that the term "screening element" may be considered as embracing both of the elements 36 and 61, or any other element in the nature of a protective partition, curtain, or shield, and in the following claims I desire this broader interpretation to be applied where that term "screening element" appears.

Variations and modifications may be made within the scope of this invention and portions of the improvements may be used without others.

I claim:

1. As an article of manufacture, an elongate hollow housing closed at both ends; a roller in said housing carrying a screen and having bearing pins at each end passing through and projecting substantially beyond the ends of the housing; brackets having apertured portions for receiving the projecting portions of the bearing pins, the aperture in one of said brackets comprising an open-ended slot, and said brackets having means for securing them to a support; and a longitudinally movable bar extending across the said open-ended slot for locking the projecting portion of the bearing pin against lateral movement out of said slot, said bar being manually retractible to free the bearing pin for lateral movement through the slot.
2. As an article of manufacture, an elongate

hollow housing closed at both ends; a roller in said housing carrying a screen and having bearing pins at each end passing through and projecting substantially beyond the ends of the housing; brackets having apertured portions for receiving the projecting portions of the bearing pins, the aperture in one of said brackets comprising an open-ended slot, and said brackets having means for securing them to a support; and means spanning the said open-ended slot for locking the projecting portion of a bearing pin against lateral movement out of the slot, said means being manually retractible to free the bearing pin for said lateral movement when desired.

3. As an article of manufacture, an elongate hollow housing; plates extending across the ends of the housing; a roller in said housing having bearing pins at each end passing through the plates and projecting beyond the ends of the housing; and a screening element carried by the roller, said housing having an elongate longitudinal opening to enable the screening element to pass therethrough, and one of said end plates and the housing having cooperable interengaging friction means whereby the plate may be quickly mounted on and removed from the housing.

4. In a window construction comprising a frame having upright side walls; brackets secured to the frame, each having a bearing pin receiving aperture therein, one of said brackets having a slot extending from an edge thereof to its said aperture; a housing; a screen roller mounted in said housing; bearing pins extending from said roller and through the ends of said housing and into said bracket apertures; and means on the slotted bracket for selectively locking the associated bearing pin therein and releasing it therefrom, whereby the housing and roller may be quickly secured to and removed from the brackets.

5. In a window construction, a frame having sash guides on its upright side walls; channels mounted on and extending along said guides for slidably receiving and supporting the opposite edge portions of a screening element; brackets secured to the frame at the top thereof; a housing; a roller mounted in said housing having

bearing pins at each end extending beyond the ends of the housing; a screening element carried by the roller, said housing having an elongate opening to enable the screening element to pass therethrough, and said brackets having apertures for receiving the said bearing pins, thereby to support the housing on the brackets, the aperture in one of said brackets comprising an open-ended slot to enable the associated bearing pin to be removed; and a longitudinal bar extending across the slot for locking the bearing pin therein against lateral movement, said bar being manually retractible to free the bearing pin for removal through the slot.

15 6. In a window construction, a frame having sash guides on its upright side walls; brackets secured to the frame at the top thereof, each having a bearing pin receiving aperture therein, one of said brackets having a slot extending from an edge thereof to its said aperture; a housing; a screen roller mounted in said housing; bearing pins extending from said roller and through the ends of said housing and into said bracket apertures; a screening element carried by the roller, said housing having an elongate opening to enable the screening element to pass therethrough; and means on the slotted bracket for selectively locking the associated bearing pin therein and releasing it therefrom, whereby the housing and roller may be quickly secured to and removed from the brackets.

FRANK ZEGA.
